UNITED STATES PATENT OFFICE.

JAMES DAMANT FAHNESTOCK, OF CINCINNATI, OHIO.

DESIGN FOR A BADGE.

SPECIFICATION forming part of Design No. 18,502, dated August 7, 1888.

Application filed June 26, 1888. Serial No. 278,261. Term of patent 3½ years.

To all whom it may concern:

Be it known that I, JAMES DAMANT FAHNESTOCK, of Cincinnati, in the county of Hamilton and State of Ohio, have invented and produced a new and original Design for a Badge, of which the following is a specification.

Reference is had to the accompanying drawings, which accompany this specification, in which—

Figure 1 represents a view in perspective, as seen from the front, of my newly-designed badge; and Fig. 2 is a perspective view of the same in part as seen from the rear.

My newly-designed badge comprises a prominent or body-like figure representing a snuff or other like box surmounted by a figure representing a rooster, and having streamers pendent from it in the form of a folded and draped bandana, representing scarf ends or "falls."

A is the box figure or ornament, b the figure of a rooster mounted thereon, and C the ornamental pendants from the box-like figure in the form of a folded and draped bandana spread out to represent scarf ends or falls.

I claim—

In the design for a badge herein shown and described, the snuff-box-like figure A, surmounted by the figure of a rooster, b, and having pendants C in the form of a folded and draped bandana spread out to represent scarf ends or falls.

JAMES DAMANT FAHNESTOCK.
